Homer A. Mead.
BY
Barlow P. Griffin
ATTORNEY.

UNITED STATES PATENT OFFICE.

EA. NEST E. LYNCH AND HOMER A. MEAD, OF TURLOCK, CALIFORNIA, ASSIGNORS TO
MASTERENCH CORPORATION, A CORPORATION OF CALIFORNIA.

WRENCH.

Application filed March 3, 1924. Serial No. 696,548.

This invention relates to a wrench especially adapted to be used with hexagonal nuts but which can, of course, be used on other nuts as well, and with serrations on the jaws, 5 can be used to turn round objects, such as pipes or rods, a single spring-operated pivoted jaw and a handle to which it is connected forming the complete wrench.

Another object of the invention is to so 10 shape the pivoted jaw that it will, in conjunction with one side of the end of the handle to which it is connected fairly and evenly contact with four sides of a large hexagonal nut.

15 Another object of the invention is to so shape the end of the handle adjacent the movable jaw that it will properly contact with the smaller sizes of hexagonal nuts in such a way as to turn them readily and without danger of slipping and marring.

Another object of the invention is to place 20 the pivot point so that its center will lie on a line extending at right angles thereto from the point to which the edge of the outer face 25 intersects the edge of the adjacent face on the movable jaw.

Another object of the invention is to so arrange the movable jaw that its outer face will be parallel to tangents to the curve forming 30 the outer end of the wrench regardless of the size of the nut that may be placed within the jaw.

Another object of the invention is to shape 35 the end of the handle adjacent the movable jaw, i. e., the fixed jaw, so that it will, in complement with the movable jaw, precisely fit four sides of the largest size hexagon nut the wrench is supposed to take.

Another object of the invention is to provide 40 an adjustable wrench which will increase the area of contact therewith as the size of the nut to which the wrench is applied increases.

Other objects of the invention will appear 45 as the description proceeds.

An embodiment of the invention is shown in the accompanying drawings in which the same reference numeral is applied to the same portion throughout, but we are aware 50 that there may be modifications thereof.

Fig. 1 is a side elevation of the wrench complete, as it appears without a nut in place therein;

Fig. 2 is an edge view of the wrench;

Fig. 3 is a side elevation of the wrench, 55 with the handle broken away showing a small sized nut therein; and

Figs. 4, 5, and 6 are similar views each showing the position the movable jaw of the wrench occupies with different sized nuts engaged thereby, the curve of the end of the fixed jaw of the wrench being determined by the various sizes of nuts to be used after the size of the largest nut has been determined. 60

The handle as indicated at 1 is of common 65 form and ordinarily made of drop-forged steel. The handle is slotted at 2 to receive the inner part 3 of the movable jaw and is pivoted at 4, the pivot being placed close to the meeting point of the flat surfaces of the 70 fixed jaw, whereby the surface 9 will be in alinement with the surface 5 when the jaws are in the full open position.

The movable jaw has a tail-piece 5' which 75 extends through the handle and enables the operator to place his thumb thereon to shift the movable jaw and hold it in any desired position when he may be attempting to turn a nut.

The movable jaw has three faces, as shown 80 at 5, 6, and 7, which said faces form portions of three sides of a hexagon.

The end of the handle forming the fixed 85 jaw has two faces 8 and 9 which form two faces of a hexagon, the pivot point 4 is arranged on a line extending from 10 to 11 which is at right angles to the face 7, the object being to give the best holding effect 90 on the nut and to prevent the jaw from either binding or slipping off.

In operation the wrench is turned clockwise (see Figs. 1 and 3 to 6 inclusive), the movable jaw being applied to the nut by the operator pressing upwardly on the tail-piece 5'. 95

The movable jaw is held against the fixed jaw normally by means of a spring 1'.

What we claim is as follows, but modifications may be made in carrying out the invention shown in the drawings and in the 100

above particularly described form thereof, said jaws are in the full open position, said fixed jaw having a curved surface adapted to engage one side of a hexagon nut while said pivoted jaw is in engagement with two 15 sides thereof.

In a wrench comprising a handle, a fixed jaw on said handle having two flat faces adapted to fit two sides of a hexagon nut, a pivoted jaw having three flat surfaces adapted to fit a hexagon nut, the pivot of said pivoted jaw being so located that a flat surface 10 on said pivoted jaw will be in alinement with a flat surface of said fixed jaw when

In testimony whereof we have hereunto set our hands this 25th day of February A. D. 1924.

EARNEST E. LYNCH.
HOMER A. MEAD.
